UNITED STATES PATENT OFFICE.

ERNEST J. LEES, OF CLEVELAND, OHIO, ASSIGNOR TO THE LEES-BRADNER COMPANY,
OF CLEVELAND, OHIO, A CORPORATION OF OHIO.

GEAR-GENERATOR.

1,071,163.

Specification of Letters Patent. Patented Aug. 26, 1913.

Application filed August 6, 1909. Serial No. 511,497.

To all whom it may concern:

Be it known that I, ERNEST J. LEES, a citizen of the United States, resident of Cleveland, county of Cuyahoga, and State of Ohio, have invented a new and useful Improvement in Gear-Generators, of which the following is a specification, the principle of the invention being herein explained and the best mode in which I have contemplated applying that principle, so as to distinguish it from other inventions.

My invention relates to gear-generating machines, generally referred to in the art as hobbing machines, whereby spur gears, worm gears, and spiral gears are cut by means of a continuously rotating cutter operating upon a continuously rotating blank.

The object of the invention is to provide a machine of the above named character embodying in its structure a maximum economy of design with a maximum efficiency of operation, and further adapted to the cutting of worms in addition to the cutting of gears of the above mentioned character.

The said invention consists of means hereinafter fully described, and particularly pointed out in the claims.

The annexed drawings and the following description set forth in detail certain means embodying my invention, the disclosed means, however, constituting but one of various mechanical forms in which the principle of the invention may be applied.

In said annexed drawings:—Figure 1 is a front elevation of a machine embodying my invention. Fig. 1^a is a rear elevation of a fragmentary portion of the machine, illustrating a detail of the construction thereof. Fig. 1^b is a front elevation of a detailed part of the mechanism. Fig. 2 is an elevation of the right hand side of the machine, as illustrated in Fig. 1. Fig. 3 is a plan of the machine. Fig. 3^a is a plan of a detail of the machine, and Fig. 3^b a plan of a segregated element of the parts shown in Fig. 3^a. Fig. 4 is a horizontal section of the machine taken upon the plane indicated by line IV—IV in Fig. 2, certain parts of the machine, however, cut by this plane being shown in elevation, parts being broken away and certain parts being omitted therefrom. Fig. 5 is a vertical section taken upon the plane indicated by line V—V in Fig. 3, certain parts of the machine being shown in elevation. Fig. 5^a is a bottom plan of a detail portion of the mechanism shown

in Fig. 5. Fig. 6 is a vertical section taken upon the planes indicated by lines VI—VI in Fig. 3. Fig. 6^a is a side elevation of the parts shown in Fig. 3^a. Fig. 7 is a vertical section taken upon the planes indicated by lines VII—VII in Fig. 3. Fig. 8 is a fragmentary vertical section taken upon the plane indicated by line VI—VI, Fig. 3, illustrating a particular adaptation of the parts therein shown. Fig. 9 is a vertical fragmentary section taken upon the plane indicated by line IX—IX, Fig. 3. Fig. 10 is a side elevation of a fragmentary portion of the left hand side of the machine, as viewed in Fig. 1, showing the arrangement of gears adapted for use in operating the machine with a single cutter, as used in cutting worms. Fig. 11 is a side elevation similar to that of Fig. 10, showing the particular arrangement of gears, used for operating with a compound cutter such as is used in generating spur or spiral gears. Fig. 12 is a section taken upon the plane indicated by lines XII—XII in Fig. 10, the gears, however, being illustrated in this figure as having axes all located in a single plane, for the purpose of greater clearness in illustrating the relationship of these gears. Figs. 13 and 14 are fragmentary axial sections of the work-rotating spindle, and taken upon the planes indicated by lines XIII—XIII and XIV—XIV, respectively, in Fig. 15. Fig. 15 is a fragmentary end elevation of such work-rotating spindle.

Referring to the drawings, the frame A is provided upon its upper surface with a horizontal slideway a, Figs. 4 and 7, which is placed at right angles with the longitudinal axis of the machine, and at the back thereof. Mounted upon this slideway is a tool-head slide B, Figs. 6 and 7, which is formed with a cylindrical seat b, having its axis horizontal and parallel with the direction of sliding movement of the tool-head slide. Mounted in this horizontal seat is a tool-head B' formed at one end with an integral flange b', and at the other end with a removable flange head b², which is suitably bolted to the head and, in conjunction with the flange b', prevents endwise displacement of the head in its seat. One edge b³ of the flange-head is graduated, as shown in Fig. 3, so as to enable the operator to determine the angular relationship of the head with the slide B, as will be readily understood.

The tool-head slide-frame member B² in

which is formed the seat b is provided with a transverse slot b^4 , Figs. 3, 4 and 6, which intersects said seat throughout an arc of substantially one hundred and eighty (180) degrees, beginning in a plane having a positive angle of forty-five (45) degrees with reference to the horizontal plane, and terminating in a plane forming a negative angle of forty-five (45) degrees with such plane. 6 The said frame member is split at b^5 , and suitable bolts b^6 b^7 are provided for drawing the split portions together, in order to bind the tool-head in its seat to assume various fixed angular positions, as will be 10 readily understood.

The flange-head b^2 is provided with a central horizontal bearing b^7 , in which is mounted a horizontal tool-driving spindle B^8 . The inner end of this spindle carries a bevel gear b^8 , which meshes with a second bevel gear b^9 , secured to the lower end of a secondary tool-driving spindle B^4 . This latter spindle is mounted in a bearing b^{10} , whose axis is perpendicular to the axis of spindle B^8 , as 20 shown in Fig. 6, and projects through the slot b^4 , as shown. The tool-head B' is formed with a gear housing, and in this housing is formed a bearing b^{11} in which the outer end of spindle B^4 is mounted. Within the housing and secured to the said spindle is a pinion B^5 , which meshes with a gear B^6 , secured to a main tool-driving spindle B^7 . The said gear is of compound form, a second gear B^8 being formed on or secured to 30 the hub of same, and of smaller diameter than the main member of gear B^6 . A bearing support B^9 is mounted upon the outer front end of the head, so as to be adjustable in the direction of the axis of said spindle, 40 and is provided with suitable binding screws, by means of which it may be fixedly secured in its slideway b^{12} , as will be readily understood.

Formed in the gear housing and adjacent 45 to the gear B^8 is an opening b^{13} adjacent to which is secured a bearing support B^{10} . In this support is mounted an auxiliary tool-driving spindle B^{11} , Fig. 6, which projects through said opening and has secured to its outer end a pinion B^{12} meshing with the gear B^8 . The lower end of this bearing support is secured to the bearing support B^9 by any suitable means, such as screws b^{14} , whereby it may be readily detached therefrom, as will 50 be readily understood. To the inner end of spindle B^{11} is secured the tool B^{13} , in this instance shown as a single cutter. The pinion B^{12} is made of considerably less diameter than that of gear B^8 , so as to permit the spindle B^{11} to be rotated at a higher rate of speed than that imparted to spindle B^7 . Where, however, it is desired to rotate the cutter at a lower rate of speed than that derived from the spindle B^{11} , as, for instance, when it is desired to generate gears 60 65

by the hobbing method, the bearing support for said spindle is removed, together with such spindle and pinion B^{12} , the latter being withdrawn through the opening b^{13} . The support B^9 may be then moved upon its slideway and may be then used as a bearing for the lower end of a mandrel B^{14} , upon which the hobbing tool B^{15} is mounted, the other end of the mandrel being driven into spindle B^7 , which is provided with a suitable tapered seat for such mandrel end, as will be readily understood. This latter arrangement is shown in Fig. 8, and is generally adopted when a compound cutter or hob is used for generating spur, worm or spiral gears, a lower rate of speed being required in this class of operations than that in which a worm, for instance, is cut by means of a single cutter.

The mechanism as thus far described forms no part of the invention as herein claimed but is separately claimed in an application filed by me Mar. 25, 1912 and bearing Serial No. 685,949.

Formed upon the frame of the machine is a horizontal slideway a' , Fig. 6, which is placed at right angles with respect to the direction of movement of the slideway a . This slideway extends longitudinally of the frame and laterally of each side of a perpendicular plane passing through the axis of the tool-head B' , as shown in dotted lines in Fig. 4. The frame A is furthermore provided with an upwardly extending portion A^5 , which is formed with a vertical and longitudinally extending bearing surface a^5 . Mounted upon this slideway is a work-carrying slide C , Figs. 1, 2, 3, 5, 6 and 7. Upon this slide is mounted work-carrying and rotating means which will be hereinafter specifically described, and which includes a rotatable spindle C' , Fig. 7, having its axis of rotation parallel with the direction of sliding movement of the slide. As shown, the slideway and slide are located so that the latter may be caused to pass along in front of the tool-holding and operating head, so as to impart to the work a path of movement such as is required in order to permit the tool to operate upon its entire length. Suitable binding screws c and a gib are provided, whereby the slide may be fixedly secured upon the frame when it is desired to give same a fixed position, Figs. 4 and 6. This main work-carrying slide C , in addition to traveling upon the slide-way a' , has its upper and forward portion formed with a surface c' which bears against the surface a^5 of the upwardly extending portion A^5 of the frame. Upon the upper surface of the main portion of the slide C is formed a guide c' extending parallel with the slide a' , and upon this is mounted a secondary part or tail-stock C^2 of the slide C . A rack c^2 is secured in this guide, extends parallel there- 100 105 110 115 120 125 130

with, and is engaged by a pinion c^3 mounted upon a horizontal spindle c^4 , to whose outer end is fixed a hand wheel c^5 . Formed upon this secondary portion C^2 of the slide, and projecting rearwardly, is an extension C^3 , whose rear end is provided with a bearing having its axis coinciding with the axis of the work-rotating spindle C' . It will therefore be seen that by turning the hand wheel 10 the extension C^3 and consequently the bearing, may be adjusted in horizontal planes with respect to the adjacent end of the work-rotating spindle C' .

The work-blank D is mounted in the usual manner, upon a suitable mandrel, one end of which is secured in the tapered bore c^6 , Fig. 7, of the spindle C' , and whose other end is mounted in the bearing, the latter being adjusted to assume the proper position 20 for receiving the particular mandrel which it is desired to employ at any specific time. When, however, it is desired, for any reason, to merely center the outer end of the work-blank-carrying mandrel, the cap c^7 , 25 Fig. 6, is removed, and in the semi-cylindrical portion of the bearing so exposed on the extension C^3 is placed a center C^4 , Figs. 3^a, 3^b, and 6^a. This center consists of the centering portion c^8 and a semi-cylindrical 30 portion c^9 , which is made to fit exactly into the said exposed semi-cylindrical bearing portion, the flat surface of this portion c^9 being thus brought flush with the exposed end of the extension C^3 . The center C^4 is 35 provided with a smooth bore c^{10} , through which projects the screw c^{11} , by means of which the center may be fixedly secured to the said extension C^3 . This particular feature of the mechanism is separately described and claimed in an application filed 40 by me Mar. 25, 1912, and bearing Serial No. 685,951. It will therefore be observed that by means of this structure, and when the center is used, such center and screw project 45 rearwardly a minimum distance, so that the operating head and tool may be brought into close proximity to the slide C, thereby permitting the tool to operate upon work of comparatively small diameter, as will be 50 readily understood by those skilled in the art. Suitable binding screws c^{12} are provided for securing the secondary part or tail-stock C^2 to the main slide member C.

By the above described arrangement of 55 the slideways and the rotatable work-rotating spindle, it will be observed that the main tool-driving arbor is adjustable about the horizontal axis of adjustment of the tool-head, the work-carrying slide has a horizontal 60 direction of feeding movement, the rotatable work-driving spindle has its axis of rotation parallel with the direction of the work-holding slide feed movement, and the axis of the said tool-driving arbor is angularly related to a horizontal plane, the slideway of

the work-carrying slide also being horizontal. Furthermore, the slideway for the work-carrying slide is intersected by a plane perpendicular to the direction of movement of the work-carrying slide and which passes 70 through the axis of adjustment of the tool-driving arbor. It will therefore be seen that by this arrangement, the work-carrying slide is always supported in the planes containing the lines of direction of the greatest stress to which the work is subjected, that is in those vertical planes which intersect the tool and are parallel with or contain the axis of adjustment. By providing the upwardly-extending portion A^5 , and the 80 bearing surfaces c^x and a^x , it will be seen that by reason of the latter's position above the slide-way a' , a further supporting element is obtained which makes for increased 85 rigidity of the structure. The work therefore is supported in a very rigid and substantial manner, and the operation is carried out without a giving of the work-supporting parts, and therefore with increased accuracy.

The sliding movement of the tool-head slide is obtained by means of a feed-screw E, Fig. 6, the rear end of which is fixedly secured to a downwardly projecting portion b^{14} of the slide, the front or threaded end of the screw being engaged by an interiorly 90 threaded sleeve E' . Keyed to this sleeve is a hand-wheel E^2 , by means of which the said sleeve may be turned. The sleeve is mounted in a bearing support c^{12} which forms a part of or is fixedly secured to the frame A, 100 and suitable means such as a rear flange e and nut e' are provided to prevent endwise movement of the sleeve with reference to bearing support c^{12} . It will therefore be seen that by turning the hand-wheel the 105 screw may be drawn forward or pushed rearwardly and the corresponding movement imparted to the slide B.

Mounted upon the main portion of the hand-wheel and forming its outer rim is a 110 ring E^3 , Figs. 1, 2, 3 and 6. This ring may be fixedly secured to the main body of the wheel by means of a set screw e^2 . Extending radially from the ring is a projection e^3 , whose function will be hereinafter fully 115 described.

Rotatably mounted on the hub of the wheel E^2 is a worm-wheel e^4 , Fig. 6, which is engaged by a worm portion e^5 fixed to or forming a part of a transverse driving shaft 120 E^4 , Fig. 1. This worm-wheel is provided with a flange e^6 adjacent to the hand-wheel, and this flange may be caused to frictionally engage the latter by means of a ring e^7 , actuated by means of screws e^8 . By this means, 125 the rotation of the worm-wheel may be caused to rotate the hand-wheel, and thereby effect a continuous feeding movement or such feeding movement may be discontinued by disconnecting the worm-wheel as above 130.

described, according as it is desired to feed the tool-head slide or not. This feature of the mechanism is specifically described and claimed in a separate application filed by me Mar. 25, 1912, and bearing Serial No. 685,950. Also mounted upon the hub of the hand-wheel is a disk e^9 , whose circumference is graduated, and which may be secured to or released from the hub by means of a thumb-screw e^{10} . By means of a suitable mark upon the adjacent surface e^{11} of the bearing support e^{12} , the angular position of the hand-wheel may be determined, as will be readily understood.

15 Mounted upon the side of the frame A and extending from front to rear thereof is a reciprocable rod F, Fig. 2. The rear end of this rod is provided with a nut f , and intermediately of this nut and the frame is a coil-spring f' . This spring normally holds the front end of the rod in its rearmost position. This front end of the rod is so located that when the rod is drawn forwardly against the action of the spring f' , it will project into the path of rotation of the projection e^3 upon the ring E^3 of the hand-wheel. Adjacent to this front end of the rod and secured thereto is a cylindrical collar f^2 , Figs. 1 and 2, and this collar is in a position such that when the rod is drawn forward against the action of the spring, its rear face may be engaged by a manually-operable dog F' , Figs. 1 and 2, such dog being oscillatorily mounted upon the frame, as shown.

20 In practice, I prefer to make the pitch of the feeding screw one-tenth (1/10) of an inch, and the entire circumference of the disk e^9 is divided into one hundred (100) graduations. By turning the hand-wheel 25 through an arc equal to one one-hundredth (1/100) of its circumference, or one graduation, the tool-head slide will therefore be fed one one-thousandth (1/1000) of an inch. The thickness of the collar is made 30 such that when the rod is drawn forward so as to cause the rear face of such collar to be engaged by the dog F' , the front end of the rod will extend into the path of the projection e^3 one-tenth (1/10) of an inch.

35 Upon the rod F and intermediately of the ends of same, is mounted a sliding collar F^2 , Fig. 2, which may be fixedly secured in any desired position therealong, by means of a suitable set screw f^3 . Depending from the slide B is a hanger b^{13} whose lower end is formed with a bore through which the rod F extends. The above described rod and the attending parts constitute means for automatically stopping the tool-head slide successively at the same point, and for the purpose of producing this result, the said parts are manipulated in the following manner.

40 Assuming now that the slide B has been 45 given the position which it is desired it shall

again occupy with exactness after having been removed therefrom, the disk e^9 is loosened from the hub of the hand-wheel and turned so as to register zero, after which it is then secured in place. The ring E^3 having been previously loosened, the rod F is drawn forward by hand so as to permit the dog F' to be lifted upwardly, whereupon the rod is released and the spring f' pulling same backwardly so as to cause the rear face of the collar f^2 to engage said dog, and hold the latter in such upward position by frictional engagement. The ring E^3 is then turned so as to cause the projection e^3 to engage the upper surface of the front end of the rod, and then secured in that position by set-screw e^2 . The collar F^2 is then loosened, slid backwardly until it engages the adjacent face of the hanger b^{13} , and then again fastened by means of the set screw f^3 . 50 The dog F' is thereupon pulled downwardly so as to disengage the collar, the rod F being, however, still retained in place by the collar F^2 . The tool-head slide B may thereupon be backed away from the work 55 by turning the hand-wheel from right to left, the operator, however, making mental note of the number of complete revolutions through which he has turned the wheel. In this backward movement, the rod F recedes 60 with the slide until it reaches its rearmost position. The slide, however, may, as will be readily understood, be moved still farther rearwardly, so as to entirely disengage the collar F^2 . Assuming, now, that it is desired to bring the tool back to exactly the 65 same position which it previously occupied, as is frequently the case in work of this class, and as will be readily understood by those skilled in the art, the hand-wheel is 70 now turned from left to right and the slide fed forwardly from the rear toward the front. During this forward movement, it reengages the collar F^2 , and immediately following such engagement, the rod again 75 moves forwardly until its front end again begins to intersect the path of the projection e^3 . By reason of the fact that the extent of such projection is made as above described, one-tenth of an inch, and one complete revolution of the hand-wheel will 80 move the slide, and therefore the rod, one-tenth of an inch, such intersection does not begin until just after the hand-wheel, and therefore the projection e^3 , has completed 85 the next to the last revolution which is necessary to bring the slide and tool back to the required position. By the time, therefore, that the last revolution is completed, the end of the rod will again be intersecting the 90 path of the projection, and the said wheel will therefore be stopped in exactly the position which it left at the beginning of the operation.

95 The shaft E^4 is mounted in a bearing A' 100

105 110 115 120 125 130

which is pivotally mounted upon a suitable journal a^2 , as shown in Fig. 1. This shaft may therefore be oscillated so as to disengage the worm e^5 , by lifting its right hand end. Such disengagement is necessary when it is desired to feed the tool-head slide manually by turning the hand-wheel E^3 , as will be readily understood. To retain this right hand end of the worm-shaft in place, a dog E^5 is pivotally mounted upon a journal screw a^3 , and has formed upon its lower end a lug e^{12} . This lug forms a seat for the lower end of a coil-spring e^{13} , which is normally in compression and whose upper end bears against the lower side of a bearing A^2 . This latter bearing is pivotally mounted upon the frame upon a journal pin a^4 secured to the frame A, and its outer end forms a bearing for the said right hand end of the shaft E^4 . The upper surface of this pivotal bearing is engaged by the dog E^5 . The direct engagement between the dog and the bearing is effected by a lug e^{14} formed on the dog, which is provided with a stepped notch e^{15} having one portion of greater depth than the other, as shown in Fig. 1^b. This notch receives the bearing A^2 and the deeper portion thereof permits such bearing to rise, by the action of the spring e^{12} , a distance sufficient to permit the worm to disengage the worm-wheel. When it is desired to cause the worm to engage the worm-wheel, the outer end of the bearing is depressed and the dog E^5 swung over to the left so as to permit the portion of the notch of less depth to engage same and hold it in such depressed position. A reversal of this operation is effected by merely swinging the dog to the right, as will be readily understood.

The shaft E^4 is driven by means of a cone-pulley E^6 , Fig. 4, which may be connected by means of a suitable belt with a second pulley E^7 driven as will be hereinafter more fully described.

I shall now proceed to describe what I shall hereinafter designate as the main driving means of the machine. This means includes primarily a cone-pulley G, Fig. 4, which is loosely and rotatably mounted upon a main driving shaft G'. In the interior of this pulley and fixed to shaft G' is a disk g, which carries a plurality of circumferentially arranged clutch pins g'. These pins are adapted to engage a plurality of similar pins g² secured upon a web g³ forming a part of the pulley and of a sleeve G², mounted upon the shaft G', slidably thereon in the direction of its axis, and rotatable therewith. The one end of this sleeve projects beyond the pulley as shown in Fig. 4, and is formed with a groove g⁴. This groove is engaged by the forked upper end of a bell crank lever H, Figs. 4 and 1^a. This lever is oscillatorily mounted upon the frame, and

has a horizontal arm h forming a handle for manual operation. The upper surface of this handle is engaged by a plunger H' mounted in a suitable housing A³ forming a part of or fixed to the frame. This housing contains a coil-spring h' which tends to move the plunger downwardly against the handle. This tendency is normally resisted by a lug h² fixed to an arm h⁴, Fig. 5, which is fixedly mounted upon a rock shaft H² mounted in suitable bearings upon the frame. The handle is provided with a lug h³, which normally rests upon lug h², as shown in Figs. 5 and 1^a.

The parts above described are so arranged that when the clutch pins g' and g² are in engagement with each other, the sleeve G² will be placed so as to impart to the handle h a position wherein the lug h³ may rest upon the lug h². Coil-springs a⁵ and a⁶ are mounted upon a pin a⁷ which is secured to the frame and passes through a suitable aperture a⁸ in the arm h⁴, the springs bearing upon opposite sides of the latter. These springs tend to maintain the arm h⁴ in a normal position in which the lug h³ may be caused to engage the lug h², as shown in Fig. 1^a. It will therefore be seen that the oscillation of the rock-shaft H² in either direction will cause the lug h² to disengage the lug h³, thereby permitting the plunger to act and throw the handle h downwardly. This action will result in carrying the sleeve G² over so as to disengage the clutch pins g' and g², and thereby disconnect the shaft G' from the pulley G. Upon one end of the shaft G' is secured a bevel gear G³, Fig. 4, which meshes with a bevel gear B¹⁶, which is fixedly secured to the sleeve B¹⁷ mounted in suitable bearings on the main frame, and rotatably and slidably connected by a spline and groove connection with the spindle B⁸, as shown in Fig. 6.

The oscillatory movement of the rock shaft H² is obtained through the instrumentality of an arm H³ mounted upon its front end, as shown in Fig. 5. The upper end of this arm is forked and embraces a rod A⁴, Figs. 1, 4, and 5. This rod is fixed to a hanger C⁶ fixed to the work-holding slide, as shown in Fig. 1, and upon this rod are adjustably fixed two collars a⁹ a¹⁰. These collars may be set upon the rod so as to engage the arm H³ during the sliding movement of said work-supporting and rotating slide C, as will be readily understood. It will therefore be seen that the main driving mechanism may be connected or disconnected at times corresponding with predetermined positions occupied by the work-holding and rotating slide.

Forming an element of the main driving mechanism is a pinion G⁴ fixedly secured to the shaft G'. This pinion engages a gear-wheel G⁵ formed with a hub g⁶, which is

mounted in a suitable bearing a^{10} forming a part of the main frame. This hub is provided with a bore in which is slidably mounted a countershaft G^s , rotatably fixed to the hub by a spline and groove connection, as will readily be understood. This countershaft has its outer end mounted in a bearing c^{17} formed upon an extension c^{18} forming a part of the frame of the work-carrying and rotating slide C. Upon the outer end of the countershaft is secured a pinion 1 which is connected with a main work-rotating shaft C^s by a chain of gears, 2, 3, 4, and 5, gears 2, 3 and 4, being mounted in a slot c^{15} upon a swinging arm c^{19} angularly adjustable upon the work-holding slide frame, as shown in Figs. 3, 4-5 and 11. This arm is formed with a slot c^{20} which, in connection with a cap screw a^{10} , permits the arm to be secured in any desired angular position, as will be readily understood.

Upon the inner end of the main work-rotating driving shaft C^s is fixedly secured a spiral gear c^{21} , Figs. 5 and 9, this gear engaging with a second spiral gear c^{22} fixedly secured to the lower end of a vertical spindle C' . This latter spindle is mounted in suitable bearings formed in a housing C^s , which itself forms a part of the frame of the work-holding slide, but is made separate therefrom and movably adjustable in a direction transverse with respect to the direction of slide-feed movement, as shown in Fig. 5. The said housing is provided with slots c^{23} c^{23} , through which pass cap screws c^{20} , by means of which the housing may be fixed to the main frame of the slide, as will be readily understood.

Intermediately of the ends of the spindle C' is secured a worm C^o , which engages a worm-wheel C^{10} fixed to the work-rotating spindle C' , as shown in Figs. 4 and 7. This worm-wheel forms one element of a compound gear, the other element of which consists of a spur-gear C^{11} , Figs. 7 and 9. Slidably mounted upon the shaft C^s , Fig. 9, is an auxiliary pinion c^{24} , which, when the worm is engaging the worm-wheel, is held in a fixed position by means of a pin c^{25} passing through an adjacent portion of the slide-frame and into an aperture formed in the pinion, as shown. The relationship of the spur-gear member C^{11} with the pinion c^{24} is such that the latter, by removing the pin c^{25} , may be slid into engagement with the former. It will therefore be seen that the work-holding spindle may be driven by the shaft C^s either through the medium of the worm-wheel and worm, or through the medium of the pinion and spur-gear. In the latter case, the housing C^s is slid over so as to disengage the worm from the worm-wheel, as will be readily understood. In order, however, to prevent any unpremeditated attempt, through carelessness, to drive the

pinion simultaneously through the medium of both sets of driving mechanisms, which would result in a breakage of parts, the housing is provided with a lug c^{26} , Fig. 5, which, when the worm is in engagement with the worm-wheel, projects into the path of sliding movement of the pinion c^{24} , thereby preventing the latter from being placed into engagement with the spur-gear C^{11} until such time as the worm is disengaged from the worm-wheel by sliding the housing in the manner previously described.

When it is desired to drive the work-holding and rotating spindle by means of the pinion and spur-gear, and the former is slid into engagement with the latter, the said pinion is rotatably secured to the shaft C^s by means of the pin c^{25} previously removed. This pin, after the pinion has been given its correct meshing position, is passed through a transverse bore c^{27} formed in the pinion's body, which registers, under these conditions, with a transverse hole c^{28} , formed in the shaft C^s , as shown in dotted lines, Fig. 9. This particular feature of the invention will be specifically described and claimed in a separate application which I shall file.

Fixedly secured to the outer end of the work-holding and rotating spindle C' is a pinion J, Fig. 4, which engages a spur-gear J' , which is rotatably fixed to a spindle J^2 mounted in a manner hereinafter described. To the inner end of this spindle is fixedly secured a clutch-member j which is adapted to engage a complementary clutch-member j^2 formed upon the adjacent face of the gear J' . The opposite side of the latter gear is formed with a hub j^3 provided with an external thread which is engaged by a threaded cap j^4 provided with suitable handles j^5 . The outer face of this cap is adapted to abut the slide frame. It will therefore be seen that by means of the above described arrangement, the rotation of the cap may be caused to throw the clutch-member j into or out of engagement with its complementary clutch-member on the gear, whereby the spindle J^2 may be placed into operative or inoperative relation with the spindle C' . The outer end of the spindle J^2 is extended so that it may receive both the pulley E^7 and the pinion 6, Fig. 11, the said pulley being provided only on such occasions where it is desired to feed the tool-holding and operating slide automatically, as will be readily understood by those skilled in the art. The pinion 6 meshes with a gear 7, which is removably mounted upon a swinging arm c^{30} , Fig. 11. This arm is mounted on the main frame coaxially with the feed-screw C^{12} , and is formed with slots c^{46} , and rotatably mounted upon the outer end of this feed screw is a gear 9, which meshes with a pinion 8, Fig. 11, secured to the gear 7. The journal of gear and pinion 7 and 8 is

adjustably securable in one of the slots c^{46} . Suitable means are provided for fixing said arms in various angular positions. It will therefore be seen that when the clutch members j and j^2 are in engagement, the rotation of the spindle C' will effect the rotation of the feed-screw C^{12} . This latter screw is mounted in the frame of the slide C , as shown in Fig. 7, and so as to be incapable of endwise movement. The inner or threaded portion of the screw engages a suitable nut C^{13} fixed to the main frame A . The rotation of this screw will therefore effect a sliding movement on the part of the work-holding and rotating slide.

The arrangement of gears just described is provided when it is desired to cut spur or other gears which are of a character such as will permit one single cut to complete the cutting operation. When it is desired to feed the slide C by hand, as is frequently required for adjustment of the work and other purposes, the clutch members j and j^2 are disengaged and a suitable handle is applied to the end of the screw C^{12} , the latter being squared for this purpose, whereby such hand-feed movement may be readily obtained. It will be noted that the hand-feeding movement of the slide is effected without rotating the work-blank.

Where it is desired to utilize the machine for cutting worms or other gears in which a single cutter is used, and the operation is performed in several cuts by a number of passes of the tool over the work-blank, a different arrangement of gears is provided, this arrangement being illustrated in Fig. 10. In the case of worms or the like, it is necessary in this feeding movement, in order to preserve the proper relationship of the work and the tool, to effect the rotating movement of the work in timed relation with the feed movement thereof, and the gears illustrated in Fig. 10 are arranged to effect such simultaneous operation. To this end, a separate set of gears is introduced, comprising a pinion 10, fixed to the shaft G^6 , and meshing with a gear 11 mounted upon the swinging arm c^{19} , the latter being adjusted to correspond with the changed diameters of the gears, and the slot therein being arranged so as to permit of the required placing of the gears thereon. Rotatably fixed to the gear 11 is a pinion 12, which meshes with a gear 13, having fixed thereto a pinion 14, which meshes with another gear 15. This latter gear also has a pinion 16, fixed thereto, and this latter pinion is capable of being connected with or disconnected from the gear 15 by means of a nut 17. The pinion 16 meshes with a gear 18 having fixed thereto a pinion 19 meshing with a gear 20, the latter mounted upon arm c^{30} and engaging a pinion 21 fixed to the feed-screw C^{12} . It will therefore be ob-

served that the rotation of the feed-screw C^{12} is effected directly from the shaft G^6 instead of indirectly therewith through the work-holding and rotating spindle C' , as in the previously described arrangement of the gears. When it is desired to rotate the feed-screw C^{12} manually, the pinion 16 is disconnected in the manner previously described, the handle applied to said screw, the latter thereby rotated without interference, the pinion 16 rotating idly upon its bearing.

The work-rotating spindle C' consists mainly of an outer hollow spindle C^{14} , Fig. 7, and an inner spindle C^{15} , capable of rotation, as will be hereinafter described, within the outer spindle. The inner spindle is provided, as previously described, with a taper bore c^6 for receiving a mandrel or the like, as will be readily understood. The inner end of the inner spindle C^{15} is formed or provided with a toothed flange c^{31} , Figs. 13, 14 and 15, and adjacent to this flange and mounted upon a bearing c^{35} formed upon the outer spindle C^{14} is a ring c^{32} . This ring is provided with slots c^{33} , through which pass cap-screws c^{34} threaded into a flange c^{35} formed upon the outer end of the outer spindle C^{14} . It will therefore be seen that the ring may be secured to or released from the outer spindle. The flange c^{35} is provided with a depression c^{37} in which is seated a cam c^{38} fixed to a stem c^{39} mounted in the ring c^{32} , as shown in Figs. 13 and 15. The outer end of the pin 100 is squared so that it may be rotated by means of a wrench. This construction therefore permits the ring to be adjusted rotatably by any small fraction of an arc, as will be understood. Upon the outer face 105 of the ring is formed a slotted lug c^{40} , in which is seated a removable dog c^{40} , one slot c^{41} being formed so as to pass transversely with relation to the spindle's axis, and the other slot c^{42} being made parallel thereto. The dog c^{40} consists of a block c^{43} which is seated in the slot c^{42} and is provided with a tooth c^{44} adapted to engage any one of the notches formed by the teeth on the outer end of the inner spindle. This dog is mounted upon a screw c^{45} which is seated in the slot c^{41} , by means of which the dog may be secured in its seat.

The number of notches provided in the flange c^{31} may be any number required, but is usually made forty-eight (48) in number. When, during the operation, it is desired to change the position of the inner spindle, and therefore the position of the work rotatably with reference to the outer spindle, the dog c^{40} is loosened and lifted out of engagement with the notches. The inner spindle may then be rotated throughout any desired angle, as will be readily understood, and then re-secured to the outer

spindle by means of said dog. When, however, it is found desirable to change the position of the inner spindle with reference to the outer spindle by an arc smaller than the pitch of the notches, the dog c^{40} is left in engagement with the particular notch in which it is secured, the cap screws c^{34} loosened, and the cam c^{36} rotated so as to rotate the ring c^{32} and therefore the inner 5 spindle, through the desired arc. This 10 specific feature of the mechanism is separately described and claimed in an application filed by me Mar. 25, 1912, and bearing Serial No. 685,952.

15 Having fully described my invention, what I claim therefore and desire to secure by Letters Patent is:—

1. In a gear-generating machine, the combination of a suitable frame; a tool-driving arbor mounted upon the latter and adjustable about an axis angularly related to its own axis; said frame formed with a main slide-way; and a work-carrying member 20 slidably mounted upon said frame and having a direction of feed-movement transverse with respect to the axis about which said arbor is adjustable; said frame being provided with an extension formed with a bearing-surface auxiliary to that formed by the 25 slide-way, and running parallel with the latter, said slide engaging said auxiliary surface.

2. In a gear-generating machine, the combination of a suitable frame formed with a main slide-way and an extension forming an auxiliary bearing surface parallel with said slide-way; a work-carrying slide mounted upon said slide-way and engaging said auxiliary bearing-surface; a tool-driving arbor 30 mounted upon the frame and adjustable about an axis right-angularly related to the direction of sliding movement of said work-carrying slide; the slide-way for the work-carrying slide and the afore-named extension being intersected by a plane which is 35 perpendicular to the direction of slide-movement, and which passes through the axis about which said tool-driving arbor is adjustable.

40 3. In a gear-generating machine, the combination of a suitable frame formed with two horizontal slide-ways at right angles with each other; a tool-head slide mounted upon one of said slide-ways; a work-holding 45 slide mounted upon the other of said slide-ways, said frame being furthermore provided with an upwardly-extending portion having a vertical bearing surface parallel 50 with the last-named slide-way; said work-

holding slide being provided with a second- 60 ary horizontal slide-way parallel with said second-named slide-way, and a tail-stock portion adjustably mounted upon said slide-way; a work-rotating member mounted upon 65 said work-holding slide; means for rotating said work-rotating member and automatically feeding said work-holding slide; main driving mechanism connected with said rotating and feeding means; a tool-head mounted in said tool-head slide and adjustable 70 about a horizontal axis; and right-angularly related with relation to the direction of feed-movement of said work-holding slide; a tool-driving arbor mounted on said tool-head; and means for driving said arbor 75 connected with said main-driving mechanism.

4. In a gear-generating machine, the combination of a suitable frame; a work-carrying slide mounted upon the latter; work-rotating means on said slide; main driving means connected with said work-rotating means; slide-feeding means; an auxiliary spindle connected with said work-rotating means; a clutch for rendering said spindle 80 operative or inoperative; adjustable arms mounted upon said frame, and gears mounted upon said arms, connecting the main driving means with said work-rotating means and with said feeding means; one of 85 said arms being adjustable in a manner such that a gear may be mounted thereon so as to connect said spindle and said feeding means.

5. In a gear-generating machine, the combination of a suitable frame; a tool-head and 90 rotatable tool-driving arbor mounted thereon, said head being slidably mounted upon said frame; a work-carrying slide mounted upon the latter and having a direction of movement right-angularly related to that of 95 said head; work-rotating means mounted upon said slide; main driving means connected with said arbor and said work-rotating means; means for automatically feeding 100 said slide and connected with said main driving means; said work-rotating means including a spur-wheel and pinion meshing therewith, and a worm and wheel, said pinion and worm mounted upon a common support 105 arranged to be moved so as to render either said spur and pinion, or said worm and wheel, operative.

Signed by me, this 3rd day of August, 1909.
